Attorney

UNITED STATES PATENT OFFICE.

WILLIAM M. HOFFMAN, OF BUFFALO, NEW YORK, ASSIGNOR, BY MESNE ASSIGNMENTS, TO OIL FUEL ENGINEERING CORPORATION, A CORPORATION OF NEW YORK.

FUEL-OIL BURNER.

Application filed May 13, 1922. Serial No. 560,579.

To all whom it may concern:

Be it known that I, WILLIAM M. HOFFMAN, a citizen of the United States, residing at Buffalo, county of Erie, State of New York, have invented a certain new and useful Improvement in Fuel-Oil Burners, and declare the following to be a full, clear, and exact description of the same, such as will enable others skilled in the art to which it pertains to make and use the same, reference being had to the accompanying drawings, which form a part of this specification.

My invention relates to fuel oil burners. The object is to provide an improved type of fuel oil burner adapted to make use of the cheaper grades of heavy, low quality fuel oils, which contain a large percentage of tarry, or other residual material in such a manner as to secure maximum efficiency at a minimum cost.

The above, and other objects together with details of construction and method of operation will more fully appear from the following description of the embodiment of my invention as illustrated in the accompanying drawings and defined in the appended claims.

In the accompanying drawings,—

Figure 1 is a vertical longitudinal sectional view through a form of my improved burner.

Fig. 2 is a rear end elevation of the burner shown in Fig. 1.

Fig. 3 is a sectional view taken on line 3—3 of Fig. 1.

Fig. 4 is a vertical longitudinal sectional view through a modified form of my burner.

Fig. 5 is a rear end elevation of the burner shown in Fig. 4.

Fig. 6 is a sectional view taken on the line 6—6, of Fig. 4.

My improved burner comprises a hollow combustion chamber casing 10, here shown in the form of a cylinder and open at one end for the discharge of products of combustion and provided with a refractory lining 11.

I prefer to construct integrally with the casing a steam pre-heater ring 13 which is positioned at the outlet of the combustion chamber and adapted to form a discharge mouth therefor. Steam is fed to this pre-heater from a suitable source of supply, which is not shown in the drawings, through a conduit 14, and conducted from the pre-heater after being heated by the exhaust

gases from the combustion chamber to a nozzle 16, which nozzle enters the rear end of the combustion chamber and is supported by the web portion 17 which extends across the rear end of the combustion chamber casing. This web construction of the rear end of the combustion chamber casing serves to provide air inlet openings 18 for the admission of air to the interior of the combustion chamber.

Positioned interiorly within the casing is a combustion chamber core 19 having an outer surface portion 19^a formed of a porous refractory material to which liquid fuel is fed to percolate therethrough so as to be burned upon the outer surface thereof. This core is so positioned within the interior of the combustion chamber as to provide an open expanse of combustion chamber there-around, being here shown as supported clear of the combustion chamber wall by means of supporting standards 20 and positioned substantially axially within the chamber.

In the construction shown in Figs. 1 and 3, the core itself is hollow and the interior serves as a well to contain liquid fuel, to which well fuel is fed through a conduit 21 from a suitable source of fuel supply not shown. The upper wall of the core is shown as perforated, as at 22, to permit the escape of fuel therethrough to the outer covering of porous refractory material through which it percolates to the outer surface upon which it is burned. These perforations may be provided in such number and so disposed as it is desired, but I prefer to locate them in the upper portion of the core, as shown in the construction shown in Figs. 4 to 6 inclusive. The core is jacketed, as shown, and the fuel is fed to the jacketed portion 23 through a conduit 21^a, as described. The jacketed portion is provided with perforations 22^a through which the fuel feeds to the outer porous refractory wall portion.

In the construction shown in Fig. 1, the core is tapered at the end opposite the discharge mouth of the combustion chamber, as shown at 24, and the nozzle 16 is so formed with a flaring mouth 25 as to project the vapor jet against the tapered end of the core so that it will flare thereover, spreading over the refractory porous wall portion and projecting the burning products of combustion toward the contracted neck or dis-

charge mouth of the burner, where the combustion is completed.

In the construction shown in Figs. 4 to 6 inclusive, the nozzle is extended into the core and the core itself is not only hollow but is open at the end nearest the discharge mouth of the combustion chamber so that the vapor jet is projected interiorly of the core toward the mouth of the burner and creates a forced draft drawing air around the core over the porous refractory wall and through the burning zone of the combustion chamber and carrying the burning products of combustion toward the contracted mouth portion where the combustion is completed.

What I claim is:

1. In a fuel oil burner, in combination, a hollow combustion chamber having an outlet for the discharge of products of combustion, a core formed of porous refractory material upon the outer surface of which combustion takes place, which core is positioned within the interior of said combustion chamber, means for projecting a vapor jet into said chamber, and a vapor pre-heater positioned at the outlet of said chamber to be heated by the discharge of products of combustion.

2. In a fuel oil burner, in combination, a hollow combustion chamber having an outlet for the discharge of products of combustion, a combustion chamber core having an outer wall portion of porous refractory material, said core positioned interiorly within said chamber spaced from the wall thereof so as to form a combustion chamber therearound, vapor jet producing means positioned so as to project a vapor jet into said chamber around said core and toward the outlet thereof, and means for feeding fuel oil to said core to percolate to the outer surface thereof.

3. In a fuel oil burner, a hollow combus-

tion chamber open for the discharge of products of combustion, a hollow core the interior of which is adapted to serve as an oil well and which is provided with an outer wall portion of porous refractory material through which fuel oil may percolate from the well to be burned upon the outer surface thereof, said core positioned interiorly within said combustion chamber spaced from the wall thereof, jet-producing means adapted to project a vapor jet into the interior of said chamber around said core, and air inlet openings to said combustion chamber around said jet.

4. In a fuel oil burner, in combination, a hollow combustion chamber having an outlet for the discharge of products of combustion, a porous refractory core positioned within the interior of said chamber upon the outer surface of which combustion takes place, said core tapered at the end furthest from the outlet of said chamber, vapor jet producing means positioned so as to project a vapor jet against the tapered end of said core and means for feeding fuel oil to said core.

5. In a fuel oil burner, a hollow combustion chamber having an opening for the discharge of products of combustion, a porous refractory core positioned within said combustion chamber, means for feeding fuel oil to said core to percolate therethrough and to be burned upon the outer surface thereof, jet producing means positioned to project a vapor jet into the interior of said combustion chamber, and means interposed intermediate said jet producing means and said core to spread the vapor jet to pass over the outer surface of the core.

In testimony whereof, I sign this specification.

WILLIAM M. HOFFMAN.
